LOCK

George Maierle, Detroit, Mich.

Application December 22, 1933, Serial No. 703,588

6 Claims. (Cl. 70—50)

This invention relates to locks and the object of the invention is to provide a lock particularly adapted for use on the gasoline tank of an automobile to prevent theft of the gasoline therefrom.

5 One of the particular objects of the invention is to provide an electrically controlled lock in which it is necessary to close an electric circuit at the time that the cap is lifted in order that the cap and lock may be removed from the 10 gasoline tank.

Another object of the invention is to provide a lock of the character described which will prevent removal of the cap from the gasoline tank and which upon being unlocked will allow removal of 15 the cap and locking member, the lock resetting itself automatically upon removal from the gasoline tank.

A further object of the invention is to provide 20 a lock member normally preventing retraction of the lock bolts, the said member being retractable from position to allow retraction of the lock bolts whereupon the lock and cap may be removed from the gasoline tank.

Another object of the invention is to provide 25 an electromagnet which may be energized to hold the lock member whereupon the cap may be lifted to retract the lock member and allow retraction of the lock bolts by means of springs provided for the purpose.

30 A further object of the invention is to provide a lock which may be applied to any container to prevent theft of the contents thereof.

These objects and the several novel features 35 of the invention are hereinafter more fully described and claimed and the preferred form of construction by which these objects are attained is shown in the accompanying drawing in which—

Fig. 1 is a section through the lock as applied 40 to a container.

Fig. 2 is a section taken on line 2—2 of Fig. 1.

Fig. 3 is a section taken on line 3—3 of Fig. 1.

Fig. 4 is a perspective view of the lock block.

Fig. 5 is a perspective view of one of the lock 45 sleeves.

Fig. 6 is a perspective view of one of the pressure applying members.

Fig. 7 is a perspective view of one of the lock bolt retainers.

50 Fig. 8 is a perspective view of one of the lock pin holders.

The device comprises a tubular member 1, shown in Figs. 1 and 2, which is welded or otherwise secured in a gasoline tank or other container 55 2 as shown. The tubular member 1 is provided

with diametrically opposite ways 3, as shown in Figs. 1 and 2, and near the lower end of each way is an aperture 4 as shown. The gasoline tank cap 5 is provided with a gasket 6, as shown in Fig. 1, and a housing 7 is secured to the cap 5 by the screws 8. Within the housing 7 is an electro-magnet comprising a coil 9 and a core or pole piece 10. The leads to the coil 9 are carried through a flexible conduit 11 to the source of current supply which, in the case of an automobile, would be the automobile starting and lighting battery. A switch, not here shown, is also preferably incorporated in this circuit and arranged as a switch button mounted on the dash of the automobile.

As shown in Fig. 3 the housing 7 is provided with lugs 12 at the lower end and a U-shaped guide frame 13 is secured to the lugs 12 by the screws 14. A lock block 15 is slidably mounted in the guide frame 13 and is normally pressed upwardly by the coiled spring 16. This coiled spring normally supports the lock block in position so that the lock member 17 normally engages the pole piece 10 of the electro-magnet. This lock member 17, as shown in Fig. 3, is provided with a square lower end 18 which fits in the aperture 19 in the lock block 15 and extends into the central bore 20 in the said block. A sleeve 21 is provided on each side of the block 15 and is made a press fit in the central bore 20 30 thereof, as shown in Fig. 2. This sleeve may be made in two pieces as shown or may be made in one piece which will extend from opposite sides of the block 15. Each sleeve is provided with a pair of pin slots 22 and with a pair of slots 23, 35 as shown in Fig. 5. Mounted in each lock sleeve 21 is a lock bolt retainer 24 having a pin aperture 25 and a lock bolt 26 is mounted in each retainer 24 and is provided with a pin slot 27, as shown in Figs. 2 and 7. A coiled spring 28 is also positioned in the lock bolt retainer 24 and tends to push the lock bolt outwardly.

Slidably mounted on each lock bolt retainer 24 is a pressure applying member comprising a collar 29 fitting about the member 24 and having two arms 30 which extend through the slots 23 in the lock sleeve 21 shown in Figs. 2 and 6. A coiled spring 31 is positioned between the collar 29 and the head 32 of the lock bolt retainer and the springs 31 tend to move the lock bolt retainers toward the center of the lock block 15. The head 32 of the lock bolt retainer is slidably mounted in the respective lock sleeve 21 and a guide ring 33 is mounted in the forward end of each sleeve 21 55

and forms a guide or support for the outer end of the respective lock bolt retainer 24. A lock pin 34 is carried by the lock pin holder 35 and this holder extends about the lock sleeve 21 and is provided with extensions at the sides to fit over the arms 30 of the pressure applying member. This lock pin 34 extends through the slots 22 in the lock sleeve 21 and through the apertures 25 in the lock bolt retainer 24 and through the slot 27 in the lock bolt 26. A coiled spring 36 is positioned between the arms 30 of the pressure applying members and the respective faces of the lock block 15, as shown in Fig. 2.

With the parts in the locked position, shown in Figs. 1, 2 and 3, the arms 30 of the pressure applying members are engaged in the way 3 in the tubular member 1 and apply a pressure to the springs 36. At the same time, a pressure is also applied to the springs 31 tending to move the lock bolt retainers inwardly but the heads 32 of the lock bolt retainers engage the opposite flat faces of the square end 18 of the lock member 17 which, in the locked position, extends between the heads 32 of the lock bolt retainers. Also in this position the lock bolts 26 engage in the apertures 4 to lock the device in position.

In operation it is necessary to do two things to release the lock. The first is to close the circuit to the electromagnet coil 9 which causes the lock member 17 to adhere firmly to the pole piece 10 and the second is to grasp the cap 5 and lift it while the circuit is closed. As the cap 5 is lifted, the electro-magnet and its housing 7 are lifted therewith thus lifting the U frame 13 and compressing the spring 16. As the electro-magnet is moved upwardly, the lock member 17 is carried upwardly therewith until the square end 18 is drawn out of the aperture 20, at which time, the springs 31 move the lock bolt retainers to the center as indicated in dotted lines in Fig. 2.

This retracts the lock bolts 26 from the apertures 4 and the lock bolts are held in the retracted position by the lock pins 34 which are carried inwardly with the lock bolt retainers 24. As the cap is lifted, the entire device may be removed from the tubular member 1 and the circuit to the electro-magnet may be broken as soon as the member 17 is lifted to position to release the lock bolt retainers. As the device is lifted out of the tubular member 1, the springs 35 move the pressure applying members 29 and arms 30 outwardly and the collar 29 at this time engages the lock pin 34 and moves it back to the position shown in Fig. 2. This carries the lock bolt retainers 24 outwardly and back to the position shown in Fig. 2, at which time, the spring 16 will draw the frame 13 and coil 9 downwardly thus moving the lock member 17 back to the position shown in Figs. 2 and 3, at which time, the end of the portion 18 extends between the lock bolt retainer heads 32. The device is then ready for replacement and by inserting it in the tubular member 1, the arms 30 which are provided with sloping lower faces, as shown in Fig. 6, are fed into the ways 3 thus moving the arms 30 toward the center of the device and placing a pressure on the springs 31 and 35 and at the same time the lock bolts 26 riding in the ways 3 place the springs 28 under pressure. As the device is moved to its lower position in the tubular member 1, the springs 28 throw the lock bolts 26 outwardly into the apertures 4 at which time, the device is again locked in the tubular member 1.

From the foregoing description it becomes evi-

dent that the device is very simple and efficient in operation, will not easily get out of order, provides a positive lock for a tank or container and provides a device which accomplishes the objects described.

Having fully described my invention, its utility and mode of operation, what I claim and desire to secure by Letters Patent of the United States is—

1. In a lock, a stationary sleeve provided with guide grooves, a cap arranged to fit over the stationary sleeve, an electro-magnet carried by the cap, a guide frame secured to the electro-magnet, a lock block slidably mounted in the guide frame, a pair of sleeves carried by the lock block, a pair of guide members slidably mounted in the sleeves and riding in the guide grooves of the stationary sleeve, a tube slidably mounted in each sleeve, a pair of spring pressed lock pins within the tubes, the stationary sleeve being provided with apertures to receive the lock pins, a lock member extending between the ends of the lock pins and normally preventing retraction of the lock pins, the lock member being retractable by energization of the electro-magnet to allow withdrawal of the lock pins from the stationary sleeve apertures. 10 15 20 25

2. In a lock, a stationary sleeve provided with guide grooves, a cap arranged to fit over the stationary sleeve, an electro-magnet carried by the cap, a guide frame secured to the electro-magnet, a lock block slidably mounted in the guide frame, a pair of sleeves carried by the lock block, a pair of guide members slidably mounted in the sleeves and riding in the guide grooves of the stationary sleeve, a tube slidably mounted in each sleeve, a pair of spring pressed lock pins within the tubes, the stationary sleeve being provided with apertures to receive the lock pins, means normally preventing retraction of the lock pins and the electro-magnet being arranged to retract said means upon energization to allow withdrawal of the lock pins from the stationary sleeve apertures. 30 35 40 45

3. In a lock, a stationary sleeve, a cap arranged to engage one end of the stationary sleeve, an electro-magnet secured to the cap, a guide frame secured to the electro-magnet, a lock block slidably mounted in the guide frame, a pair of lock pins carried by the lock block, the sleeve being provided with apertures to receive the lock pins, a lock member normally extending between the ends of the lock pins and preventing retraction of the lock pins, the lock member being retractable by energization of the electro-magnet. 50 55 60

4. In a lock, a stationary sleeve, a cap arranged to engage over the stationary sleeve, an electro-magnet carried by the cap, a guide frame secured to the electro-magnet, a lock block slidably mounted in the guide frame, a pair of lock pins carried by the lock block, the stationary sleeve being provided with apertures to receive the lock pins, means normally preventing retraction of the lock pins from the stationary sleeve apertures, said means being retractable by energization of the electro-magnet to allow withdrawal of the lock pins from the stationary sleeve apertures. 65 70 75

5. In a lock, a stationary sleeve, a cap arranged to fit over the stationary sleeve, an electro-magnet carried by the cap, a guide frame secured to the electro-magnet, a lock block slidably mounted in the guide frame, a pair of sleeves carried by the lock block, a lock pin slidably mounted in each sleeve, the stationary sleeve be- 75

ing provided with apertures to receive the lock pins, means normally preventing retraction of the lock pins and the electro-magnet being arranged to retract said means upon energization.

5 6. In a lock, an electro-magnet, a guide frame secured to the electro-magnet, a lock block carried in the guide frame, a pair of lock pins car-

ried by the lock block, a lock member carried by the lock block and extending between the ends of the lock pins to normally prevent retraction of the lock pins, the lock member being retractable upon energization of the electro-magnet. 5
